UNITED STATES PATENT OFFICE.

JOSEPH W. BERNET, OF NEW LONDON, CONNECTICUT.

FOOT-OPERABLE IMPRESSION THROW-OFF.

1,350,272.

Specification of Letters Patent. Patented Aug. 17, 1920.

Application filed November 29, 1918. Serial No. 264,682.

To all whom it may concern:

Be it known that I, JOSEPH WILLIAM BERNET, a citizen of the United States, residing at New London, in the county of New London and State of Connecticut, have invented new and useful Improvements in Foot-Operable Impression Throw-Offs, of which the following is a specification.

This invention comprehends generally improvements in that class of inventions known as printing and more particularly has reference to a foot operable impression throwoff.

It is the primary aim and object of the present invention to provide a device of the above mentioned character designed for use on job printing presses of the Chandler & Price or Gordon types and is capable of being operably connected with the main shaft 20 of the impression throwoff mechanism and operable by the foot thereby leaving both hands of the feeder free to straighten the sheets resulting in increased speed by means of a greater output, greater accuracy in registering less spoilage and a result in general decrease in the cost of producing any printing job.

More particularly the present invention contemplates the provision of a device of the above mentioned character wherein a swingable foot pedal is designed to be mounted on the floor and near one side of the press and arranged in operable position relative to the shaft of the impression throwoff mechanism while acting in conjunction with the pedal is resilient means for normally holding the impression throwoff mechanism inactive.

It is a more specific object of this invention to provide a device of the above mentioned character wherein a locking element of an improved construction is employed for relatively holding the impression throwoff mechanism in an operative position.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction here-

inafter described and the scope of the application which will be indicated in the appended claims.

The invention is clearly illustrated in the accompanying drawings, in which:

60

Figure 1 is a side elevation showing the attachment in position on a printing press.

Fig. 2 is a top plan view thereof.

Fig. 3 is a front elevation thereof.

Fig. 4 is a side elevational detail looking 65 toward the foot pedal and showing the same in an inactive position.

Fig. 5 is a detail view of the lock member.

Similar characters of reference are employed in all of the above described views, 70 to indicate corresponding parts.

Referring now, more particularly, to the accompanying drawings there is illustrated a portion of a job printing press of the Chandler & Price type and includes generally spaced side frames 1 and an oscillatory shaft 2 of the impression throwoff mechanism of the press (not shown). Connected to the outer projecting end of the shaft 2 is an arm 3 while operably connected with the arm and mounted on the floor near the press is the improved attachment indicated in its entirety by the numeral 4.

In reducing the invention to practice a pair of standards 5 are employed and are formed at their lower ends with feet 6 which are secured by suitable fasteners 7 to the floor and positioned parallel with and on opposite sides of one of the side frames 1. These standards terminate at their upper ends in bearings 8 in which is journaled a shaft 9. An arm 10 is disposed about one projecting end of the shaft 9 and secured thereto by means of a set screw 11. A connecting rod 12 is now employed and has one end connected to the arm 3 by means of a pin 13 while the opposite end is connected to the arm 10 by means of a pin 14. A contractile coiled spring 15 has its forward end connected to the pin 14 and its opposite 90 end operatively connected to a friction sleeve 16 loosely disposed on the shaft 2 and tensioned so as to normally hold the throwoff mechanism (not shown) in an inactive position.

A foot pedal 17 has its inner sleeve end 18 secured to the other projecting end of the shaft 9 by means of a set screw 19. A connecting rod 12 is now employed and has one end connected to the arm 3 by means of a pin 13 while the opposite end is connected to the arm 10 by means of a pin 14. A contractile coiled spring 15 has its forward end connected to the pin 14 and its opposite 95 end operatively connected to a friction sleeve 16 loosely disposed on the shaft 2 and tensioned so as to normally hold the throwoff mechanism (not shown) in an inactive position.

A foot pedal 17 has its inner sleeve end 18 secured to the other projecting end of the shaft 9 by means of a set screw 19. When pressure is exerted on this foot pedal by the foot of the attendant the shaft 9 will be rocked and the arm 10 swung forwardly 100

100

105

110

and by reason of the connection of the connecting rod 12 with the arm 3 the latter arm will be swung forwardly to rock the shaft 2 and thereby actuate the throwoff mechanism.

5 When it is desired to maintain the throw-off mechanism in an inactive position suitable locking means is employed in the present instance consisting of a lock member generally designated by the numeral 20 comprising a base portion 21 having spaced slots 22 therein through which are arranged fasteners 23 for slidably mounting the member 20 on the floor or equivalent support so that it is shiftable laterally into and out of the 10 path of the foot lever. This lock member is preferably formed from a single piece of strap metal while an upright portion 24 continues from the base portion and continuing from the upright portion and disposed parallel above the base portion is a 15 horizontal pedal engaging portion 25. A foot engaging flange 26 is formed at the terminal of the foot pedal engaging portion 25 to facilitate shifting of the lock member 20 into and out of operative position relative to the foot pedal as is apparent.

It is believed in view of the foregoing description that a further detailed description of the operation of the invention is entirely unnecessary. Likewise it is believed 30 that the advantages of the invention will be readily apparent. However, it is to be observed particularly that by the provision of the present foot pedal attachment 35 which is employed instead of or to supplement the usual hand lever the operator of the press is enabled to quickly apply the impression throwoff mechanism leaving his hands free to feed and straighten the sheets 40 and thereby resulting in the saving of a considerable amount of sheets that would otherwise be spoiled should the operator or feeder

fail to have sufficient time to apply the throwoff mechanism.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention which as a matter of language might be said to fall therebetween.

What is claimed is:

60 A foot actuatable throwoff attachment for printing presses consisting of a rock shaft having connected therewith a link for attachment to the crank arm of the throwoff shaft and a contractile spring provided with a terminal sleeve for engagement with said throwoff shaft, a pedal carried by the rock shaft, means for supporting the rock shaft in convenient relation to the front of the machine, and a locking member mounted for movement into and out of the path of the pedal and consisting of a slotted base of which the slots are engaged by guide pins or bolts, a standard having an offset or shoulder for engagement with the pedal when the locking member is in the path of the latter, and a terminal upstanding projection at the extremity of said offset for engagement by the foot of the operator to move said member into and out of operative relation with the pedal.

In testimony whereof I affix my signature.

JOSEPH W. BERNET.
